UNITED STATES PATENT OFFICE.

JOHN W. NASMITH, OF MANCHESTER, ENGLAND.

COMBING MACHINE.

1,367,076.

Specification of Letters Patent.

Patented Feb. 1, 1921.

Application filed May 27, 1919. Serial No. 300,115.

To all whom it may concern:

Be it known that I, JOHN WILLIAM NASMITH, of Leegate, Mauldeth Road, Heaton Mersey, Manchester, England, have invented certain new and useful Improvements in Combing-Machines, of which the following is a specification.

In the now well known Nasmith combing machine the feed is made by means of a fluted roller having an intermittent forward rotation in bearings fixed in relation to the nipper plate, the roller resting on the material and pressing it against the said plate. This method is open to one objection especially when feeding forward such material as a thick lap of short cotton. Such a lap is composed of layers of fibers superposed one upon the other and building up a considerable thickness and it happens that when the fluted roller revolves the material in contact with the flutes moves forward with the flutes while the lower layers in contact with the stationary plate, along which they should slide, do not in fact move forward sufficiently, notwithstanding the smoothness of the plate, to keep pace with the upper layers and by degrees this retardation of the lower layers causes an accumulation and bunches of material which, from time to time are carried through and tend to damage the needles and give rise to uncombed patches of material passing into the fleece to the detriment of the work.

The object of my invention is to overcome this defect. To do so I mount the roller in bearings which are movable to and fro in relation to the nipper plate. As the nipper moves forward toward the detaching roller, the fluted feed roller gripping the material between itself and the plate is pushed forward bodily on the plate while suitable means are employed to prevent it from revolving when moving in this direction so that it and the material beneath it are simply pushed forward on the plate the required amount. When the nipper makes its return movement the roller is released and simply rolls back over the material to its initial position ready for the next stroke, so that if the lower layers have not quite kept pace with the upper ones, the roller rolls over them and no accumulation takes place, the error being corrected each stroke.

In order that the invention may be better understood a sheet of drawings is ap-

pended showing one method in which the requisite movement of the roller may be obtained. Figure 1 is an end elevation of a nipper constructed according to my United States Letters Patent No. 724,119 to which the invention is applied and Fig. 2. that of a nipper constructed according to my British Letters Patent No. 3871/14 to which the invention is applied and it will be understood that it may be applied to other forms.

In the form of my invention illustrated in Fig. 1 A¹ is the cylinder shaft on which is mounted the cylinder A. D is the detaching roller. N¹ is a pivot fixed in the framing of the machine on which a pair of nipper arms (one at either end of the nipper) N, bound together by the bridge B. oscillate, so that the studs S carried one in each arm N, travel to and fro from S to S¹ along the dotted arc C. C. F. is the feed roller resting on the nipper plate P² and carrying, fixed on one end the ratchet wheel E. The studs P¹, on which the top nipper arms pivot in the actual machine, are prolonged to engage in the slots Z formed in the feed levers F¹, which fork the feed roller at each end. But in the arrangement shown in Fig. 2. the studs P¹ are not used but special pins P are fixed in the nipper frame. The feed levers F¹ have formed in them slots H to receive the pins G, fixed in one end of the cranked levers L, which pivot freely on the studs S fixed in the nipper arms N. It will be understood that all these levers are in pairs, one at each end of the nipper. One of the levers F¹ has cast upon it the projection F², to which is pivoted a pawl X engaging with the ratchet E. Levers V suitably pivoted and weighted in the usual manner press constantly on the levers F¹ and keep the roller F firmly down on the material between it and the plate P². It is obvious that if the levers F¹ be moved to the left the roller F will roll freely over the plate, but if moved in the opposite direction, the pawl X engaging with the teeth of the ratchet E will prevent the roller from turning so that it is simply pushed along the plate.

R. is a rod fixed in the framing of the machine and hinging on it a rod T, provided with adjusting nuts T¹ T² passes through the swivels W, which hinge freely on the pins I. These pins I can be fixed in any position in the slots O, formed in the levers L, which pivot freely on the studs

S. As the studs S travel along the arc C. C to the position S¹ the pins I move along the arc Y. Y having R as center, to the position I¹. The levers L consequently turn 5 on the studs S until the pins G assume the position G¹ and draw back the feed levers F¹, the reverse taking place as the studs move forward from S¹ to S. The position 10 of the roller F on the plate P² can be adjusted by the nuts T¹ T² and the amount of its displacement, that is the amount of feed can be varied by varying the position of the studs I in the slots O.

In the form of my invention illustrated 15 in Fig. 2, A^{1r} is the cylinder shaft on which is mounted the cylinder A^r. D^r is the detaching roller. N^{1r} is a pivot fixed in the framing of the machine of which a pair of 20 nipper arms (one at either end of the nipper per) N^r, bound together by the bridge B^r oscillate so that the studs S carried one in each arm N^r travel to and from S to S¹ along the dotted arc C^r. C^r. F^r is the feed roller resting on the nipper plate P^{2r} and carrying 25 fixed on one end the ratchet wheel E^r. The feed levers F^{1r} have formed in them slots H^r to receive the pins G^r fixed in one end of the cranked levers L^r, which pivot freely on the studs S^r fixed in the nipper arms N^r. It 30 will be understood that all these levers are in pairs, one at each end of the nipper. One of the levers F^{1r} has cast upon it the projection F^{2r}, to which is pivoted a pawl X^r engaging with a ratchet E^r. Spring 35 weighted levers V^r suitably pivoted and weighted in the usual manner press constantly on the levers F^{1r} and keep the roller F^r firmly down on the material between it and the plate P^{2r}. It is obvious that if the 40 levers F^{1r} be moved to the right the roller F^r will roll freely over the plate, but if moved in the opposite direction, the pawl X^r engaging with the teeth of the ratchet E^r will prevent the roller from turning so 45 that it is simply pushed along the plate.

In Fig. 2 the studs S fixed in the nipper arms N travel a short distance along the dotted arc C. C passing through the center of S, the amplitude of this oscillation being 50 shown by the dotted radii C¹, C². The studs I travel along the inner and shorter arc and have hinged upon them the rods T passing through bell-mouthed holes in the fixed bar R. On the rods T are adjusting nuts T¹ 55 T² above and below the bar R. As the studs I descend along their arc no movement of the parts takes place until the descent of T is arrested by the nuts T¹ coming in contact with the bar R. I is then ar- 60 rested while S continues and lever L turns on S and as described in the former case, moves the feed levers F¹ forward. The position of the roller F on the plate P² is 65 regulated by the position of the nuts T¹ T² on the rod T and the amplitude of its move-

ment on the plate by the distance between the nuts.

What I claim and desire to secure by Letters Patent is:—

1. In a combing machine, a plate on which the material to be combed rests, a roller mounted to move back and forth along said plate in proximity thereto, and being adapted to move forwardly without rotation and to roll back over said fiber to its initial position. 70

2. In a combing machine, a plate on which the material to be combed rests, a roller mounted to move back and forth along said plate in proximity thereto to feed the material resting thereon, means associated with said roller whereby it is prevented from rotating during its forward movement in feeding said material and is permitted to rotate during its return movement. 80

3. In a combing machine, a plate on which the material to be combed rests, a roller for feeding the material forwardly along said plate, bearings adapted to reciprocate back and forth along said plate in which said roller is mounted, a ratchet-wheel rigidly connected with said roller and a ratchet co-operating therewith in such manner that when the roller is moved forwardly along said plate, said roller is prevented from rotating on its axis but is permitted to rotate during its backward stroke to facilitate its passage over said material. 90

4. In a combing machine, a nipper frame pivotally mounted thereon for oscillation, a plate rigidly mounted on said nipper frame on which the material to be combed rests, levers pivoted by means of studs intermediate of its ends to said frame, a feed roller suitably connected with said lever and adapted to rest on said material and to be reciprocated thereon to feed said material along said plate, a rod connected to the opposite end of said levers and means on said rod for regulating the position of the roller on the plate and the amount of the feed thereof. 100

5. In a combing machine, a nipper frame pivotally mounted thereon for oscillation, a plate rigidly attached to said nipper frame 115 on which the material to be combed rests, a lever pivoted intermediate of its ends to said frame, a feed roller carrying member attached to one end of said levers and adapted to be reciprocated adjacent said plate, a feed roller mounted in said member and adapted to rest on said material, a rod adjustably and pivotally attached to the opposite end of said lever whereby the position of the roller at any time in the movement of said frame is determined and said levers having slots therein, and a stud on said rod extending into said slots whereby the length of the path of movement of said roller may be 120 regulated. 125

6. In a combing machine, a nipper frame pivotally attached thereto, a plate rigidly attached to said frame upon which the material to be combed rests, a lever pivoted 5 intermediate of its ends to said frame, a member slidably arranged on said frame and pivotally connected with the lower end of said lever, a roller journaled in said member and adapted to rest on the material on said plate, and adapted to be moved forward and 10 backward thereon, and means on said lever for regulating the distance the roller moves on said plate and means for determining the position of said roller on said plate 15 at a given time.

7. In a combing machine, a nipper frame pivotally attached thereto, a plate rigidly attached to said frame upon which the material to be combed rests, a lever pivoted 20 intermediate of its ends to said frame, a

member slidably arranged on said frame and pivotally connected with the lower end of said lever, a roller journaled in said member and adapted to rest on the material on said plate, and adapted to be moved forward and 25 backward thereon, and means on said lever for regulating the distance the roller moves on said plate and means for determining the position of said roller on said plate at a given time, and means on said roller co- 30 operating with means on said member whereby the roller is prevented from rotation on its forward movement and permitted to rotate on its backward movement.

In testimony whereof I have affixed my 35 signature in the presence of two witnesses.

J. W. NASMITH.
